Another series of openings 24 at the foot of the device, has displayed over it the word "Honors" while below the openings is another set of slides 25 having handle elements 26 and bearing respectively the characters 5 "A, K, Q, J, 10," representing ace, king, queen, jack and ten spot, that is the five highest cards.

A distinguishing line of color 27 appears 10 on the second and third row of sliders, in addition to the symbols, this line clearly showing if the slide has been shifted from the normal position, as shown in Fig. 1, to a raised position as in Fig. 2, the red line showing, for 15 instance that the honor card was held by the bidder and if the line does not appear, that the card was held by the dummy thus showing whether the honors were all in one hand or divided.

Obviously in a no trump game the honors 20 can only be the 4 aces, and in such case the symbols on the middle row of sliders are used to indicate the honors held by the bidder and the dummy, the bottom row of sliders in this 25 case being "clear."

Fig. 2, indicated that three spades was bid, the bid doubled, that spades are trumps and that the ace and jack have been played from the dummy hand and that king, queen and 10 30 have been played from the hand of the bidder, obviously and possible range of occurrences may be indicated by properly adjusting the slides.

In the modification shown in Fig. 6, the upper plate is provided with circular openings 35 30 below which are slides 31 in all respects like those previously described except that in place of a central handle element, an up-standing tab 32 is formed on one end of the slide.

It is believed that those who have use for 40 a device of this character will amply understand the way in which it is to be used without further elaboration, as it is self evident to an auction bridge player.

Although the foregoing is descriptive of the preferred embodiment of the invention, it will be apparent that minor changes may be made in the construction, without the exercise of invention or conflicting with the 50 scope of the claim hereto appended.

Having thus described my invention, what I claim as new and desire to secure by Letters Patent, is:—

55 A card game indicator for auction bridge comprising a casing composed of two spaced plates united at their marginal edges, one of said plates having a series of ridges to contact the other plate, the last named plate 60 having three rows of five openings, respectively denominated bid, trump and honors, an individual slide movable in the space between said plates into and out of registration with each opening, and a single legend carried by each said slide denoting the amount 65

of the bid, trump and honor cards played, respectively.

Signed in the city, county and State of New York this 23rd day of February, 1928.
